UNITED STATES PATENT OFFICE

130,418

DESIGN FOR A WATER GLASS SUCTION SUPPORT

Jack Reynolds, Long Island City, N. Y.

Application February 10, 1941, Serial No. 98,861

Term of patent 7 years

To all whom it may concern:

Be it known that Jack Reynolds, a citizen of the United States, residing at Long Island City, in the county of Queens and State of New York, has invented a new, original, and ornamental Design for the Water Glass Suction Support, of which the following is a specification, reference being had to the accompanying drawing, forming a part thereof.

Figure 1 is a side elevational view of a water glass suction support showing my new design.

Figure 2 is a front elevational view.

Figure 3 is a top plan view of the same.

I claim:

The ornamental design for a water glass suction support, substantially as shown.

JACK REYNOLDS.
